(57) **CLAIM**

The ornamental design for a smart personal water container, as shown and described.

DESCRIPTION

FIG. 1 is a front, top, right, perspective view of a smart personal water container, according to an embodiment of the design.

FIG. 2 is a front side view of the smart personal water container, according to the embodiment of the design.

FIG. 3 is a rear view of the smart personal water container, according to the embodiment of the design.

FIG. 4 is a left side view of the smart personal water container, according to the embodiment of the design.

FIG. 5 is a right side view of the smart personal water container, according to the embodiment of the design.

FIG. 6 is a top view of the smart personal water container, according to the embodiment of the design; and,

FIG. 7 is a bottom view of the smart personal water container, according to the embodiment of the design.

The broken lines shown in the figure drawings are included for the purpose of illustrating environment and form no part of the claimed design.

1 Claim, 6 Drawing Sheets
